UNITED STATES PATENT OFFICE.

ROBERT L. WATKINS AND ROBERT HEAD, OF NEW YORK, N. Y., SAID HEAD ASSIGNOR TO
SAID WATKINS.

PHOTOMICROGRAPHIC APPARATUS.

No. 921,317.

Specification of Letters Patent.

Patented May 11, 1909.

Application filed June 26, 1908. Serial No. 440,438.

To all whom it may concern:

Be it known that we, ROBERT L. WATKINS and ROBERT HEAD, both citizens of the United States, and residents of the city, 5 county, and State of New York, have jointly invented certain new and useful Improvements in Photomicrographic Apparatus, of which the following is a specification.

Our present invention relates in general 10 to an improved apparatus for making photographs of magnified images of small or microscopic objects and more particularly has for its object such an apparatus distinguished by features among others, first, the 15 entire apparatus including microscope, camera, lamp, and accessories are adapted to be combined in one connected piece of apparatus; second, these parts are so related and interconnected as to fold up and 20 telescope within the camera box of the apparatus, which then acts as a small, compact carrying case for the entire apparatus. In addition, other features or advantages of the 25 present invention will appear from the following specification.

In the drawings which show only one of the forms which our improvements may take, Figure 1 is a view partly in vertical section and partly in elevation of my apparatus as same appears when folded up; Fig. 30 2 is a side elevation of the same when unfolded, the particular condition shown being that immediately preceding the step of inserting the photographic plate holder to 35 take a picture; Fig. 3 is an end elevation of the apparatus in the same condition as in Fig. 2, looking at the said apparatus from the right hand of said figure; Fig. 4 is an elevation looking at the apparatus from the 40 back of the microscope with the camera box unhinged and the bottom section thereof lowered on the microscope tube to give access to the eye-piece in order that the operator may conveniently view the object from 45 said eye-piece; Fig. 5 is an enlarged horizontal section partly in plan on the line 5—5 in Fig. 4; Fig. 6 is a vertical section partly in elevation of a detail; Fig. 7 is a 50 top plan view of the pan 41 and related parts.

Describing now our invention with particular reference to the devices of the drawings, and reserving it to the claims to point 55 out the novel features, said devices shown comprise generally speaking a microscope

A, a combined camera and carrying-box B, and a lamp C. The microscope A, comprises a base 1, a pillar 2, and a tube 3. At the upper end of the tube may be mounted an eye-piece 4 and at its lower end an objective 5. It will be noted in the particular form shown that the microscope tube is rigid on the pillar, the focusing being brought about by the up and down adjustment of the stage 6, which is of the movable type sliding on 60 rods 7 secured to the pillar 2.

The means shown for adjusting the stage comprises a vertical rack 8 on the inside of the pillar 2 and a pinion 9 in mesh therewith and mounted on a stem 10 having a knurled-head 11 secured thereto at one end, said stem having bearings 12 secured to the sliding support 13 which upholds the stage. Obviously turning the knurled-head in one direction or the other acts to elevate or lower 75 the stage on the rods 7.

The slide containing the preparation or object to be viewed and photographed may be supported as usual on top of the stage by the down pressure of the spring-clips 14. 80 Also as usual the stage may have a central opening to permit light to pass up from below through the slide into the microscope tube. Also a diaphragm 15 which may be of the iris type, may be provided to control 85 the amount of light. The diaphragm may be operated by turning the knurled-head 16, Figs. 2 and 3.

A shutter 17 is provided, operable by moving the presser arm 18, to close or open at 90 will the stage opening against the entrance of light from below through the stage-opening. It is this shutter which is operated when taking the picture, the shutter being of any usual or preferred type. 95

A condenser 19 is shown mounted on a lateral extension from the stage supporting member 13. From the same member a mirror 20 is universally supported below the condenser to be tilted to any desired angle 100 to properly reflect the light from the arc lamp C (Fig. 2) up through the stage-opening and microscope tube.

The lamp C is shown folded into carrying position in Fig. 1, and in unfolded or operating position in Figs. 2 and 3. The lamp shown is of the arc type comprising carbons 21, adjustable to and away from each other, the upper carbon being intended to be the positive carbon, in other words, the car- 105 110

bon in which the crater forms, to obtain the benefit of the intense light therefrom, which being directed downward is best adapted to be reflected by the mirror up the microscope tube.

The supporting frame for the carbons, best shown in Figs. 1 to 3, is designated 22, and has connected thereto a pair of horizontally extending rods 23 one over the other. 10 Connecting these rods with the microscope base 1 are side members 24, two on a side, and each pivotally connected at one end with the microscope base and being connected at the other end with one of the rods 15 23. The purpose of the construction is to permit the carbon supporting frame 22 to be swung into and out of the positions shown in Figs. 1 and 2, and for this purpose the lower side members 24 (compare 20 end view in Fig. 3) are located inside the upper side members so that the former can clear the latter and occupy the same vertical plane when they are in the upturned position shown in Fig. 1. The upper side 25 members 24 will preferably be hollow tubes in order to permit the wire connections to the lamp to pass through them, as will be hereinafter described.

The means for attaching the carbons comprises first, a clamp 25 on the frame 22 for the lower carbon; and second, a vertically adjustable support for the upper carbon comprising in the particular form shown a pair of uprightly extending rods 26 and 27 30 from the frame 22, a clip 28 suitably perforated to slide up and down on the said rods, one of which 27 is screw-threaded and is engaged above the clip by a knurled nut 29 and below the clip is surrounded with a 35 spiral spring 30, which holds the clip elevated against the knurled nut. A clamp 31 is carried by the clip to receive and hold the upper carbon. Obviously by adjusting the knurled nut 29, one way or the other, the 40 upper carbon is raised and lowered relative to the lower carbon to properly form and regulate the arc.

The electrical connections to the lamp comprise a pair of terminals 32, located in the 45 particular device shown in insulating bushings 33 through the rear of the microscope base, only one of these being shown in Fig. 1, the other being directly in back, on the same plane. From the terminals 32, an insulated wire 34 proceeds to a resistance coil 35 mounted permanently at the base of the microscope. The actual inclosing box 36 for the resistance coil would ordinarily be made of perforated metal to provide for the circulation of air to the coil to avoid heating. 50 The other end of the resistance leads by an insulated wire 37, passed through one of the tubular side members 24 to the supporting clamp 25 of one of the carbons. Whereas 55 the supporting clamp 31 of the other carbon

connects by an insulated wire 38, passed through the other tubular side member 24, with the second terminal 32, which as already stated is in back of that shown in Fig. 1. Obviously this completes the circuit for the 60 lamp, it being only necessary to connect a source of electricity to the terminals 32 to start up the lamp in manner well known.

Passing now to a description of how the box or case B serves in two-fold capacity, 75 first, as an inclosing or carrying case, as in Fig. 1; and second, as a camera box shown in Figs. 2 and 3, it will be noted from Fig. 1 that by disengaging the catch 39, the box B can be raised vertically off its bottom 80 to expose the microscope and permit the lamp to be hinged down into its operative position shown in Fig. 2.

To describe how the box B is supported in its elevated position of Fig. 2, it is necessary in the first place to describe the member 41 to which the box is adapted to be secured. This member is best seen in vertical section in Figs. 1 and 6, and in top plan in Fig. 7, and comprises what may be called a 85 shallow rectangular pan having an opening through its bottom provided with a surrounding sleeve 42 adapted to receive through it the microscope tube. This sleeve has secured concentrically to its underside a locking ring 43, the securing means comprising pins 44 (Fig. 6) located in circular concentric slots through the locking ring, pins being secured to the sleeve 42 and the locking ring 43 permitting a partial turn to 90 95 give to the locking ring. On the opposite sides of the microscope tube are two pairs of vertical splines 45 separated by an intervening space, these splines being adapted to the work in corresponding vertical grooves in the interior of the sleeve 42 and locking ring 43 respectively.

It will be noted upon referring to Figs. 1 and 6, that the length of the upper pair 100 of splines is equal to the height of the sleeve 42, whereby when the pan 41 is elevated from the position in Fig. 1 to the position in Fig. 6, the locking ring 43 will be located in the space between the upper 105 and lower set of splines, whereby upon turning said ring so that its spline receiving groove is out of line with the spline, the bottom of said ring will ride up on the ends of the lower splines which being inclined 110 upwardly, as indicated in Figs. 1 and 6, force the bottom of the pan into binding contact with the overhanging flange 46 of the microscope tube or rather against a washer 47 of yielding material interposed 115 for the purpose. Thus the simple act of turning the locking ring in one direction or the other when the pan is in elevated position serves to lock or unlock said pan from 120 the microscope tube. 125 130

Upon comparing Figs. 1 and 6 it will be noted that the pan has an overhanging rim 48 adapted to be engaged by a correspondingly inwardly projecting flange 49 around the sides of the box B when the latter is elevated as shown in Fig. 6. The object of this is to prevent the entrance of light into the box B at the joint between it and the pan, while taking the picture.

10 The means for removably securing the box in the position shown in Fig. 6 comprises in the particular form shown a pair of stems 50 projecting through the bottom of the pan 41 provided with exterior handles 51 convenient to twist the stems about their axis, said stems being supported above in bearings 52 secured to the inside walls of the pan, said stems having at their upper ends cam-heads 53 (see Figs. 6 and 7,) the 15 inclined faces 54 of which are adapted to take under the lower end of vertical strips 55 secured to the interior of the box B, when the handles are suitably operated for the purpose. Said handles being also 20 adapted to be operated to withdraw the cams from under the strips and thereby permit the box to be lowered.

It will be noted (Fig. 7) that the pan is oppositely slotted in vertical direction at 56 30 to permit the passage of the strips 55 in lowering the box.

The box B at its upper end is provided with a cover 57 hinged at 58, the box having high sides 59 at its mouth shown vertically slotted at 60. A ground glass frame 61 is located between the sides 59, and springs 62 are provided one on either side with one of their ends 62^a anchored and their other longer ends 62^b connected to the 40 ground-glass frame through the vertical slots 60. The purpose of the construction is to give the ground-glass frame a normal downward tendency so that it closes the mouth of the camera box B in suitable position for viewing the image, at the same time that it permits a plate holder to be inserted between the end of the box and itself, when taking the pictures. This or any other suitable mounting of the ground-glass 45 frame may be provided for the described purpose. It will be noted that the camera box is also adapted to be hinged apart at 63 (see Figs. 2, 3 and 4) a suitable clasp 64 being provided to hold the two portions of 50 the box together as in Fig. 3.

Describing now the general operation of the described devices, it will be assumed that they are folded up into the contained form shown in Fig. 1. To unfold them it is only necessary to release the catch 39 and then to elevate the box B away from the bottom of the box until the lamp C is clear to permit it to be swung down into the position shown in Fig. 2. The box B may 65 then be fastened to the pan 41 by manipu-

lating the fastening devices 51 as previously described. Next the clasp 64 (Fig. 3) may be released and the top of the box swung down into the position shown in Fig. 4. At this time the pan is still in its lowermost 70 position of Fig. 1, which is the position also occupied in Fig. 4, in order that accessibility can be had by the operator to the eye-piece of the microscope. Similarly it is for this same reason that the box is made hingeable 75 at 63. The operator will now insert his slide or other preparation on the microscope stage and will manipulate the condenser, mirror, etc., for proper lighting to view the object and will then adjust the stage to and 80 from the objective by operating the knurled head and will if necessary manipulate the slide or preparation and do such other necessary things as to properly center the field desired to be photographed. The lamp 85 C will then be connected in circuit and lighted, and the camera box hinged back into its upright position of Figs. 2 and 3. Next the pan 41 will be raised on the microscope tube and the ring 43 locked, whereupon the operator will look through the ground-glass and will manipulate the mirror, condenser and iris diaphragm, and other lighting devices to give the proper illumination and also will manipulate the stage adjusting devices until a sharp focus is obtained of the image on the ground glass. Next the shutter 17 will be closed and a plate holder will be inserted underneath the ground glass and its slide withdrawn. 100 Whereupon opening the shutter for the necessary interval will expose the sensitive plate, which will thereafter be developed as usual. Then the apparatus can be again folded up as in Fig. 1 where it will be observed that the camera box serves as a container for the apparatus, a handle 65 being provided at the side to conveniently carry it. Moreover when folded up, it will be noted that there is no waste space and 110 further that the microscope is supported against movement in all directions.

Auxiliary means is shown in Figs. 1, 2, 4 and 7 for viewing the image on the screen of ground glass or other suitable material 115 without opening the lid 57 to view said image from the top end of the camera box in the usual manner, said auxiliary means comprising in the particular form shown a cylindrical casing 66 closed at its bottom 120 and communicating above with an opening through the bottom of the pan 41. A mirror 75 is contained at a suitable reflecting angle within the casing 66 to permit the viewing of the image on the screen through 125 the eye-opening 70, the latter being in the end of a tube 69 connected with a sleeve 68 movably surrounding the cylindrical casing 66, said casing having an opening 67 in its side adapted to register with the open- 130

ing in the tube 69 when the tube 69 is swung into position shown in Fig. 1, whereby looking through the eye-opening 70 permits the image on the screen to be viewed as reflected in mirror 75. Of course it will be understood that the device will be used when the pan 41 is in its uppermost position on the microscope tube 3 with the camera box B also in its uppermost position as for example shown in Fig. 2. At such time, the operator looking through the eye-opening 70 and manipulating the focusing and other adjusting and lighting devices can focus the image sharply on the screen preparatory to making an exposure without removing the cover 57 or otherwise manipulating devices at this end of the box.

When not in use, the tube 69 can be swung at right angles to its position in Fig. 1, so as to bring it within the four sides of the box in folding up and putting away the apparatus. I further provide means for giving vertical adjustment to the lamp C when in its lowered or operative position, said means comprising a projection or lug 71 rigid with one of the side bars 24 and adapted to contact with the end of a set screw 72 working in a bracket 73 from the base 1 of the microscope, whereby adjusting said set screw in one direction or the other raises or lowers the said supporting arms 24 and consequently the carbon carrying frame within the desired limits of vertical adjustment.

Having thus described our invention, what we claim is:

1. A photomicrographic apparatus comprising in combination a microscope, a box adapted to act both as a container for the microscope and as a camera box, comprising a bottom at the microscope base, sides separable from said bottom and elevatable into picture taking position, a secondary bottom surrounding the microscope tube adapted to have a light-tight joint with the sides of the box when in elevated position and to be secured thereto, said box near its top end being adapted to receive a sensitive film.

2. A photomicrographic apparatus comprising in combination a microscope, a box adapted to act both as a container and as a camera box, comprising a bottom at the microscope base, sides separable from said bottom and elevatable into picture taking position, a secondary bottom surrounding the microscope tube adapted to have a light-tight joint with the sides of the box when in elevated position and to be secured thereto, said box near the eye-piece end of the microscope tube being separable to give the operator access to the eye-piece, and said box toward its top end being adapted to receive a sensitive film.

3. A photomicrographic apparatus comprising in combination a microscope, including a stage and stage lighting devices; a

lamp pivotally supported from the microscope base adapted to be elevated in upright position over said base and to be lowered into operative position to radiate light upon the stage lighting devices of the microscope; a box adapted to act both as a container and as a camera box comprising a bottom at the microscope base, sides separable from said bottom and elevatable into picture taking position, a secondary bottom surrounding the microscope tube adapted to have a light-tight joint with the sides of the box when in elevated position and to be secured thereto, said box toward its top end being adapted to receive a sensitive film.

4. A photomicrographic apparatus comprising in combination a microscope having a base, pillar and tube with vertically adjustable stage having a shutter adapted to control the stage opening, and means for lighting said stage; and a combined container and camera box having a bottom at the microscope base, sides separable from said bottom and elevatable into picture taking position, a secondary bottom surrounding the microscope tube adapted to have a light-tight joint with the sides of the box when in elevated position, said box toward its top end being adapted to receive a sensitive film.

5. A photomicrographic apparatus comprising in combination a microscope, a box adapted to act both as a container and as a camera box having its bottom at the microscope base with sides separable from said bottom and elevatable into picture taking position, a secondary bottom with sleeve-surrounded opening having sliding fit with the microscope tube and adapted to be secured in a given position thereon, said bottom being adapted to have a light-tight joint with the sides of the box when in elevated position, and to be secured thereto, said box toward its top end being adapted to receive a sensitive film.

6. A photomicrographic apparatus comprising in combination a microscope; a box adapted to act as a combined container and camera box, said box having its bottom at the microscope base, sides separable from said bottom and adapted to be elevated into picture taking position, a secondary bottom surrounding the microscope tube and having up and down adjustment thereon, said bottom being adapted to have a light-tight connection with the sides of the box when in elevated position, said box at the eye-piece end of the microscope being separable to give access by the operator to the eye-piece and being adapted toward its top end to receive a sensitive film.

7. A photomicrographic apparatus comprising in combination a microscope; a combined container and camera box having its bottom at the microscope base, sides elevat-

- able off said bottom into picture taking position, a secondary bottom with sleeve-surrounded opening having a sliding fit with the microscope tube, said sleeve being 5 splined on said tube, which latter has an overhanging top flange, said sleeve having a locking ring also splined on said tube, which ring when the secondary bottom is in elevated position against the overhanging 10 flange on the microscope tube, is adapted to be turned to bring the bottom of said ring into locking contact with the ends of the splines on the microscope tube, which at this point are discontinuous, said secondary bot- 15 tom being adapted to have a light-tight joint with the sides of the box when in elevated position and to be secured thereto.
8. A photomicographic apparatus comprising in combination a microscope, a fold- 20 ing arc lamp pivotally connected to the microscope base adapted to be brought into elevated position over said base and when in said position to be inclosed by the sides of a box telescoped over the microscope, 25 said lamp when lowered out of elevated position being adapted to furnish light to the microscope, and comprising a carbon supporting frame adapted to support the carbons in vertical relation adjustable to and 30 from each other, said frame being pivotally connected by side members to the microscope base.
9. A photomicographic apparatus comprising in combination a microscope; an arc 35 lamp comprising a carbon supporting frame adapted to support the carbons in vertical relation and adjustable to and from each other, said frame being pivotally connected by hollow side members to the microscope 40 base to be elevated into vertical position over said base and to be lowered as desired into operative position with the carbons vertical; electrical connections to said carbons including leads passed through said 45 hollow side members and a resistance at the
- base of the microscope; and a box adapted to be telescoped down over the microscope with its sides inclosing the arc lamp in ele- 5 vated position.
10. A photomicographic apparatus comprising in combination a microscope; a camera box operatively connected therewith, said camera box having a screen adapted to have focused upon it the image; and a mirror mounted in connection with the camera 55 box adapted to reflect through an eye-opening the image on the screen.
11. A photomicographic apparatus comprising in combination a microscope; a lamp; a lamp-supporting member pivotally 60 connecting the lamp and the microscope base; and adjustment means between said member and the microscope base comprising a screw on one of said parts adjustable in contact with the other to raise and lower 65 the lamp-supporting member.
12. A photomicographic apparatus comprising in combination a microscope; a camera box operatively connected therewith, said camera box having a screen adapted to have 70 focused upon it the image, said camera box having an opening through its bottom leading to a cylindrical casing; said casing containing a mirror positioned to reflect the image from the screen through an opening 75 in the side of the casing, said casing being surrounded by a rotatable sleeve having an opening adapted to register with the opening through the casing and carrying at said opening a tubular extension with end eye- 80 opening.

In witness whereof we have signed our names to the foregoing specification in the presence of two subscribing witnesses.
